UNITED STATES PATENT OFFICE.

ARTHUR E. PAIGE, OF PHILADELPHIA, PENNSYLVANIA.

ROTARY PUMP.

Application filed March 12, 1926. Serial No. 94,174.

My invention relates to pumps of the type including a pair of gears which are intermeshed and rotated in a casing, so as to carry a liquid in the toothed spaces of said gears 5 from an inlet to an outlet in said casing, and is particularly designed and adapted for use in the art of forming what are known as artificial silk threads by the extrusion of a colloid, such as the thiocarbonate of cellulose 10 known as viscose, through a spinneret orifice, into a coagulating medium such as an aqueous solution containing sulphuric or hydrochloric acid.

The form of my invention hereinafter described is adapted to supply such a colloid, under pressure, through a conduit leading to a single spinneret. That pump is arranged to be driven by driving gearing which may be common to an extensive series of similar 20 pumps, and includes adjustable means for selectively rendering it operative and inoperative, at the will of the operator, so that each pump may be separately controlled without interference with the others. Such individual pump controlling means is arranged to axially shift the driven gear on the pump out of mesh with the driving gear by which it is normally rotated, and without interrupting the rotation of said driving gear, so that a 25 series of such pumps may be operatively connected with the same train of driving gearing and may be individually selectively rendered operative and inoperative without interference with each other and without interrupting the continued operation of the 30 driving gearing.

The quantity of liquid to be delivered to the spinneret is extremely small and, consequently, the slightest fluctuation in the volume or 40 rate of such delivery would be manifest in irregularities in the filament extruded from the spinneret. Therefore, it is an object and effect of my invention to provide a construction and arrangement capable of extreme accuracy of construction, to insure its regularity of performance. Moreover, in pumps of the construction ordinarily employed for the purpose above contemplated, the means for rendering the pump operative or inoperative 45 with respect to its driving gear, have involved the pump conduits or passageways for the liquid; requiring adjustment of the conduit connections both to initiate and terminate the operation of the pump; with the consequence that slight wear upon the movable

joints causes leaks therein through which air is sucked into the stream of colloid being delivered through the pump, and is occluded as bubbles therein which, of course, are forced into the filament extruded through the spinneret and cause the extruded filament to break at the portions thereof thus aerated, when subjected to tensile strains which the normal filament is entirely capable of withstanding. Therefore, an advantageous feature of my invention is that the possibility of such infiltration of air is avoided by so constructing and arranging the passageways for the liquid through the pump that they are not disturbed by any adjustment or manipulation to control the operation of the pump by engagement and disengagement of its actuating mechanism.

My invention includes the various novel features of construction and arrangement 75 hereinafter more definitely specified.

In said drawings; Fig. I is a plan view of a pump conveniently embodying my invention. Fig. II is a vertical sectional view of said pump, taken on the line II, II in Fig. I. 80 Fig. III is an inner face view of the pump mechanism as removed from its base. Fig. IV is a fragmentary sectional view, showing a modified form of adjustable driving gear. Fig. V is a plan view of a pump including a 85 modified form of my invention, in connection with a viscose supply conduit. Fig. VI is an end elevation of the structure shown in Fig. V, with said conduit indicated in section. Fig. VII is an elevation of the opposite end of said structure shown in Figs. V and VI. Fig. VIII is a longitudinal sectional view of said structure, taken on the line VIII, VIII in Fig. V.

In Figures I to IV inclusive; the pump base is conveniently formed as a single iron or steel casting of L-shaped cross section, including the horizontal flange 1 with openings 2 for screw attaching means, and the vertical flange 3 having screw threaded pipe sockets 4 and 5 therein for respective permanent connection with the inlet pipe 7 and outlet pipe 8. Said vertical base flange 3 has two screw threaded holes 10 extending therethrough at the upper portion thereof and two similar 100 screw threaded holes 11 extending therein at the lower portion thereof, and has its face 12 machined and ground plane to accurately fit the hardened steel pump chamber plate 13 which has its opposite faces ground in 110

parallel planes. Said plate 13 is thus made to accurately fit against said base face 12 and has two holes 15 arranged to respectively register with said holes 10 in the vertical base flange 3 and has two holes 16 arranged to register with said holes 11 in said base flange. Said pump chamber plate 13 has the inlet port 18 and outlet port 19 formed by drilled holes extending therethrough and in communication with the sectoral circular openings 20 and 21 which also extend therethrough and are accurately ground to fit the perimeters of the two gears 23 and 24 which have respective teeth 25 and 26 intermeshed in closely fitted relation, in the pump chamber 14, intermediate of said ports 18 and 19.

Said gears 23 and 24 are normally maintained in the accurately spaced relation shown in Fig. III, by the pump frame plate 28 which may be an iron or steel casting having its inner face 29 accurately ground plane, to fit said plate 13. Said frame plate 28 has two holes 30 and two holes 31 therein respectively registering with the holes 15 and 16 in said plate 13; and also has two holes 32 registering with said ports 18 and 19 and normally closed by the screw plugs 33 in alignment with the respective pipes 7 and 8 and affording access to the interior of said pump chamber and pipes. Said pump chamber plate 13 and frame plate 28 may be accurately assembled and rigidly connected, in the position shown in the drawings, by the three screws 34 and the screw 35 which extend through the registered holes in said frame plate 28 and plate 13 into the screw threaded holes in said base flange 3. Said screws 34 have heads 36 which bear upon the outer face of said frame plate 28 to clamp the latter in the position shown; but said screw 35, which has the head 37, is provided with the nut 38 for engagement with the outer face of said frame plate 28 and not only serves to clamp the latter in the position shown, but is also adjustable to render the pump alternately operative and inoperative, as hereinafter described.

Said gear 23, which is driven as an idler by the other gear 24, is conveniently rigidly connected with the stud shaft 40 which may be drive fitted therein and which shaft is journaled in the bearing 41 bored in said frame plate 28. I find it convenient to provide said frame plate 28 with the drilled and tapped hole 42, in coaxial relation with said shaft bearing 41, so that the shaft 40 may be pushed out of said bearing if, from any cause, it becomes stuck therein. However, said hole 42 is normally hermetically closed by the screw 43 and gasket washer 45.

Said gear 24 is arranged to be positively rotated by the shaft 47 upon which it may be rigidly secured, but is preferably slip fitted; said shaft having the key 48 extending therefrom in the keyway 49 in said gear so as

to positively engage and rotate the latter if connected therewith in either way. Said shaft 47 is journaled in the bearing 51 in said frame plate 28 and extends through the stuffing box 52 in which the packing 53 is arranged to hermetically seal the joint between said shaft 47 and its bearing 51. Said shaft 47 has the keyway 54 at its outer end for engagement with the key screw 55 which extends therein through the hub of the gear wheel 56, which is slip fitted on said shaft. The roller 58, which is slip fitted on said bolt 35 and pressed against the head of the latter by the spring 59 encircling said bolt, engages the toothed perimeter of said gear wheel 56 as indicated in Figs. I and II; so that said gear 56, while otherwise free to slide axially upon its shaft 47, is normally held in mesh with the gear 60 of the train whereby said pump is arranged to be operated. However, any pump thus constructed and arranged may be instantly rendered inoperative by axial movement of the bolt 35, in either direction, to the axial extent of the toothed face of said gear 56. However, such adjustment is preferably effected by unscrewing said bolt 35, outwardly, from the position shown in Figs. I and II, in which it is normally clamped by pressure of the nut 38 thereon against the outer face of said frame plate 28.

It is to be particularly noted that the adjustment last above described, whereby any pump in a series connected with the driving train of gearing may be individually and instantly operatively connected with or disconnected from said train, may be effected without interrupting the operation of said driving train or any of the other pumps connected therewith. Such construction and arrangement are advantageous to permit the cleaning of any of the individual spinnerets connected with such pumps when the orifices thereof become clogged with particles of solid matter occluded in the viscose or other colloid being extruded therethrough.

The form of my invention above described is advantageous in that the bolt 35 may be set, by its nut 38, to detain the respective pump gear 56 in either operative or inoperative position, without possibility of accidental displacement of such gear. However, I have shown a simpler embodiment of my invention in Fig. IV, wherein the shaft 47, arranged to drive the gear 24 as above described, is provided with the gear 62, in lieu of the gear 56, and differing therefrom only in that the gear 62 has the web 63 closing its hub at the outer end and affording an abutment for the spring 64, which is mounted in the socket 65 in said shaft 47 so as to normally maintain said gear 62 in mesh with the driving gear 60. However, said gear 62 may be instantly disengaged from said driving gear 60, to render the pump inoperative, by moving said gear 62 axially, against the

pressure of said spring 64 and conveniently by a cone pointed push rod 66, such as a lead pencil, which may be conveniently thrust in the axial opening 67 in said hub web 63, as indicated in dotted lines in Fig. IV. Such axial movement may be effected while the gear wheel 62 is rotating; but said wheel may be held in disengaged position by clamping its set screw 55 against said shaft 47, in the 10 keyway 54 in said shaft.

As the operation of pumping viscose tends to wear the metal from the walls of the pump chamber at the opposite plane faces of said pump gears 23 and 24, causing leaks and loss 15 of efficiency, I find it desirable to interpose face plates of hardened steel between said pump chamber plate 13 and the adjacent faces of the base and frame plate, as hereinafter described.

Although in the foregoing description, I have respectively designated the pipes 7 and 8 as inlet and outlet pipes; it may be observed that the construction and arrangement of the pump are so symmetrical that the pump gears 25 may be rotated in either direction and, consequently, either of said pipes may be the inlet and the other the outlet. Such construction and arrangement are advantageous in that they facilitate the washing out of the 30 pump connections by operating the pump alternately in opposite directions.

However, said inlet pipe may be omitted and the pump base directly connected with a 35 supply conduit having a series of supply ports; so that said conduit serves to support a series of similar pumps respectively local to the supply ports therein, as shown in Figs. V to VIII inclusive.

In Figs. V to VIII inclusive: the pump 40 base 71 has the conduit channel 72 between the laterally extending bolt flanges 73 and the plane faced flange 75 extending transversely to said bolt flanges 73 in lieu of the flange 3 above described. Said base 71 has the inlet 45 port 76 extending from said conduit channel 72 to the plane face of said flange 75, and the outlet port 77 extending from said plane face of said flange 75, in spaced relation with said inlet port 76 and leading through a conduit 50 78 to the spinneret 79. Said base has the gasket seat 80 surrounding said inlet port 76 in said conduit channel 72 and has a series of screw threaded bolt holes 81 in its flange 75.

The clamp plate 83 has the conduit channel 55 84 between laterally extending bolt flanges 85 and complementary to the channel 72 and flanges 73 in said base 71. The bolts 86 are provided with nuts 87 and arranged to connect said flanges 73 and 85 and clamp the conduit 60 88 in rigid relation with said base 71, to supply the viscose or other liquid to be pumped. The resilient gasket 89, conveniently formed of soft rubber, is fitted in said gasket seat 80 and arranged to register with the supply port 90 in said conduit 88 and to 65

seal the junction of said supply port 90 with said inlet port 76 when said base and clamp plate are clamped together as shown.

The pump chamber plate 91 has the series of bolt holes 92 adapted to register with the bolt holes 81 in said base flange 75, and has two ports 94 and 95 respectively adapted to register with said inlet port 76 and outlet port 77, and has the pump chamber 96 between said ports. The face plates 98 and 99 75 are fitted upon respectively opposite sides of said pump chamber plate 91 and have respective series of bolt holes 100 and 101 adapted to interchangeably register with the bolt holes 81 in said base. As shown in the drawings, said plates 98 and 99 are alike and symmetrical, so that they may be reversed or replaced to compensate for wear upon the inner faces thereof by the gears in the pump chamber formed between them. The frame plate 85 102 has the series of bolt holes 103 adapted to register with the holes in said chamber plate, face plates and base, and has two shaft bearings 104 and 105 registering with said chamber, said bearing 104 being of less axial 90 extent than the thickness of said frame plate; the other of said bearings, 105, extending through said frame plate 102 and having the stuffing box 107 and gland 108 in coaxial relation therewith. The through shaft 110 extends in said through bearing 105 and stuffing box and gland and carries the key 111 at the inner end thereof, extending in said chamber 96 and limiting the outer movement of said shaft 110. The pump gear 113 has the 100 seat 114 for said key 111 and is detachably connected with said keyed shaft 110 within said chamber 96. The other pump gear, 115, extends in said chamber 96, in mesh with said first pump gear 113 and has the short stud 105 shaft 116 rigidly connected therewith, extending in said short shaft bearing 104 in said frame plate 102. The driving gear 118 is rigidly connected to the outer end of said keyed shaft 110, by the set screw 119 and may 110 be driven by an intermediate gear 120 connecting it with the driving gear 121 as indicated in Fig. VII. Said intermediate gear 120 is journaled on the stud shaft 123 which is rigidly connected with the bearing plate 115 124. Said plate 124 is fitted to turn upon said stuffing box 107 and has the slot 125 in registry with one of the tap bolts 126. Said plate 124 may be rigidly clamped against said plate 102, in the position shown in Fig. 120 VIII, in which said pump gearing is operatively connected, or, by loosening said bolt 126, said plate 124 may be turned to disengage said intermediate gear 120 from the driving gear 121 and thus render the pump 125 idle without interference with any other pump in the series. There are four of said tap bolts extending through said frame plate, face plates, and pump chamber plate, into engagement with said screw threaded holes 130

81 in said base flange 75, to hold said plates in assembled rigid relation with said base; whereby all of the movable parts of said pump may be removed from said base, by removing said tap bolts 126, without disturbing said base or the pipe lines 78 and 87 connected therewith.

I do not desire to limit myself to the precise details of construction and arrangement 10 herein set forth, as it is obvious that various modifications may be made therein without departing from the essential features of my invention as defined in the appended claims.

I claim:

15. 1. In a rotary pump, the combination with a base having means whereby it may be maintained in stationary position and including a vertical flange provided with an inlet pipe socket and an outlet pipe socket 20 upon one side thereof and having a plane face upon the opposite side thereof and a series of screw threaded bolt holes; of a pump chamber plate having a series of bolt holes adapted to register with the bolt holes 25 in said base, two ports adapted to register with said inlet and outlet, and a pump chamber between said ports; a frame plate having a series of bolt holes adapted to register with the holes in said chamber plate and base and having two shaft bearings registering with said chamber, one of said bearings having an opening 30 through said frame plate and removable means arranged to seal that opening; the other of said bearings extending through said frame plate and having a stuffing box and gland in coaxial relation therewith; means arranged to seal said screw threaded opening, including a screw plug and a gasket; the other of said 35 bearings extending through said frame plate and having a stuffing box and gland in coaxial relation therewith; a shaft extending in said through bearing and stuffing box and gland, having a keyway at the outer end thereof and carrying a key, at the inner end thereof, extending in said chamber; a pump gear connected with said 40 keyed shaft within said chamber; another pump gear, in said chamber, in mesh with said first pump gear and having a shaft connected therewith, extending in said other shaft bearing in said frame plate; a driving 45 gear fitted to the outer end of said keyed shaft, in axially adjustable relation therewith; means arranged to adjustably present said driving gear in mesh with a driving train and to detain said gear in disengaged 50 position, at the will of the operator, including a roller embracing the edge of said driving gear, a screw bolt extending through said roller, frame plate, and chamber plate and engaging said base, a nut on said bolt arranged to jam said bolt in adjusted position, and a spring, encircling said bolt, between said nut and roller, arranged to normally maintain said roller against the head of said bolt; whereby the axial position of the head of said bolt determines whether said driving gear is in operative or inoperative position; and other bolts 55 extending through the registered openings in said frame plate and chamber plate in engagement with said 60
- 65

base; whereby said pump may be rendered operative or inoperative by axial movement of the driving gear, and all of the movable portions of said pump may be removed from 5 said base, without disturbing said base or the pipe lines connected therewith.

3. In a rotary pump, the combination with a base having means whereby it may be maintained in stationary position and including 10 an inlet pipe socket and an outlet pipe socket upon one side thereof and a plane face upon the opposite side thereof and a series of bolt holes; of a pump chamber plate having a series of bolt holes adapted to register with the 15 bolt holes in said base, two ports adapted to register with said inlet and outlet, and a pump chamber between said ports; a frame plate having a series of bolt holes adapted to register with the holes in said chamber 20 plate and base and having two shaft bearings registering with said chamber, one of said bearings having means arranged to hermetically close its outer end; the other of said bearings extending through said 25 frame plate and having a stuffing box and gland in coaxial relation therewith; a driving shaft extending in said through bearing and stuffing box and gland, and extending in said chamber; a pump gear detachably connected with said driving shaft within said 30 chamber; another pump gear, in said chamber, in mesh with said first pump gear and having a shaft connected therewith, extending in said other shaft bearing in said frame 35 plate; a driving gear fitted to the outer end of said keyed shaft, in axially adjustable relation therewith; means arranged to adjustably present said driving gear in mesh with a driving train and to detain said gear 40 in disengaged position, at the will of the operator, including a spring, arranged to normally maintain said gear in operative position, and a screw arranged to detain it in inoperative position; and other bolts extending 45 through the registered openings in said frame plate and chamber plate in engagement with said base; whereby said pump may be rendered operative or inoperative by axial movement of its driving gear, and all of the 50 movable portions of said pump may be removed from said base, without disturbing said base or the pipe lines connected therewith.

4. In a rotary pump, the combination with a base having means whereby it may be maintained in stationary position and including 55 an inlet pipe socket and an outlet pipe socket upon one side thereof; of a pump chamber plate having two ports adapted to register with said inlet and outlet, and a pump chamber between said ports; a frame plate having two shaft bearings registering with said 60 chamber; two shafts journaled in said bearings; two pump gears respectively connected with said shafts and meshed within said chamber; a driving gear fitted to the outer 65

end of one of said shafts, in axially adjustable relation therewith; and means adjustable to present said driving gear in mesh with a driving train and to detain said gear in disengaged position, at the will of the operator; 70 whereby said pump may be rendered operative or inoperative by axial movement of its driving gear, and all of the movable portions of said pump may be removed from said base, without disturbing said base or the pipe lines 75 connected therewith.

5. In a rotary pump, the combination with a base having means whereby it may be maintained in stationary position and including an 80 inlet pipe socket and an outlet pipe socket upon one side thereof and having a plane face upon the opposite side thereof; of a pump chamber plate having two ports adapted to register with said inlet and outlet, and a pump chamber between said ports; a frame plate having two shaft bearings registering with said chamber; two shafts journaled in said bearings; two pump gears respectively connected with said shafts and meshed within 85 said chamber; a driving gear fitted to the outer end of one of said shafts; and means adjustable to present said driving gear in mesh with a driving train and to detain said gear in disengaged position, at the will of the operator; 90 whereby said pump may be rendered operative or inoperative and all of the movable portions of said pump may be removed from said base, without disturbing said base or the pipe lines connected therewith.

6. In a rotary pump, the combination with a base having a conduit channel between laterally extending bolt flanges, and a plane faced flange extending transversely to said bolt flanges, having an inlet port extending from said conduit channel to said plane face, 100 and an outlet port extending from said plane face, in spaced relation with said inlet port, a gasket seat surrounding said inlet port in said conduit channel and a series of screw threaded bolt holes in said plane faced flange; of a clamp plate having a conduit channel between laterally extending bolt flanges and complementary to the channel and flanges in said base; bolts arranged to connect said flanges and clamp a conduit in rigid relation with said base; a resilient gasket fitted in said gasket seat, arranged to register with a supply port in said conduit and to seal the junction of said supply port with said inlet port; 110 a pump chamber plate having a series of bolt holes adapted to register with the bolt holes in said base flange, two ports adapted to register with said inlet and outlet, and a pump chamber between said ports; face plates fitted upon respectively opposite sides of said pump chamber plate, having a series of bolt holes adapted to register with the bolt holes in said base; a frame plate having a series of bolt holes adapted to register with the holes in 115 said chamber plate, face plates and base and 120

125

130

having two shaft bearings registering with said chamber, one of said bearings being of less axial extent than the thickness of said frame plate; the other of said bearings extending through said frame plate and having a stuffing box and gland in coaxial relation therewith; a shaft extending in said through bearing and stuffing box and gland and carrying a key, at the inner end thereof, extending 10 in said chamber, limiting the outer movement of said shaft; a pump gear detachably connected with said keyed shaft within said chamber; another pump gear in said chamber, in mesh with said first pump gear, and 15 having a shaft rigidly connected therewith, extending in said other shaft journal in said frame plate; a driving gear fitted to the outer end of said keyed shaft; bolts extending through said frame plate, face plates and pump chamber plate, into engagement with 20 said screw threaded holes in said base flange, arranged to hold said plates in assembled rigid relation with said base; whereby all of the movable portions of said pump may be removed 25 from said base, without disturbing said base or the pipe lines connected therewith.

7. In a rotary pump, the combination with a base having a conduit channel and a plane faced flange extending transversely to said channel, having an inlet port extending from said conduit channel to said plane face, and an outlet port extending from said plane face, in spaced relation with said inlet port, and a 30 series of bolt holes in said plane faced flange; of a clamp plate having a conduit channel complementary to the channel in said base; means arranged to connect said base and plate and clamp a conduit in rigid relation with said base; means in said base channel arranged to register with a supply port in said conduit and to seal the junction of said supply port with said inlet port; a pump chamber plate having a series of bolt holes adapted 35 to register with the bolt holes in said base flange, two ports adapted to register with said inlet and outlet, and a pump chamber between said ports; a frame plate having a series of bolt holes adapted to register with the holes in said chamber plate and base and having two shaft bearings registering with 40 said chamber, one of said bearings being short and of less axial extent than the thickness of said frame plate; the other of said bearings being long and extending through said frame plate; a through shaft extending in said 45 through bearing and into said chamber; another pump gear in said chamber, in mesh with said first pump gear, and having a short shaft rigidly connected therewith, extending in said short shaft journal in said frame 50 plate; and driving means connected to the outer end of said through shaft; bolts extending through said frame plate and pump chamber plate, into engagement with said 55 bolt holes in said base flange, arranged to hold said plates in assembled rigid relation with said base; whereby all of the movable portions of said pump may be removed from said base, without disturbing said base or the pipe lines connected therewith.

60 8. In a rotary pump, the combination with a base having a conduit engaging flange and a plane faced flange with an inlet port to said plane face, and an outlet port extending from said plane face, in spaced relation with said inlet port, and a series of bolt holes in said plane faced flange; of means arranged to hold 65 a conduit in communication with said inlet; a pump chamber plate having a series of bolt holes adapted to register with the bolt holes

in said short shaft journal in said frame plate; and driving means connected to the outer end of said through shaft; bolts extending through said frame plate, face plates and pump chamber plate, into engagement with 70 said bolt holes in said base flange, arranged to hold said plates in assembled rigid relation with said base; whereby all of the movable portions of said pump may be removed from said base, without disturbing said base 75 or the pipe lines connected therewith.

9. In a rotary pump, the combination with a base having a conduit channel and a plane faced flange extending transversely to said channel, having an inlet port extending from 80 said conduit channel to said plane face, and an outlet port extending from said plane face, in spaced relation with said inlet port, and a series of bolt holes in said plane faced flange; of a clamp plate having a conduit channel complementary to the channel in said base; means arranged to connect said base and plate and clamp a conduit in rigid relation with said base; means in said base channel arranged to register with a supply port in said conduit and to seal the junction of said supply port with said inlet port; a pump chamber plate having a series of bolt holes adapted 85 to register with the bolt holes in said base flange, two ports adapted to register with said inlet and outlet, and a pump chamber between said ports; a frame plate having a series of bolt holes adapted to register with the holes in said chamber plate and base and having two shaft bearings registering with 90 said chamber, one of said bearings being short and of less axial extent than the thickness of said frame plate; the other of said bearings being long and extending through said frame plate; a through shaft extending in said 95 through bearing and into said chamber; another pump gear in said chamber, in mesh with said first pump gear, and having a short shaft rigidly connected therewith, extending in said short shaft journal in said frame 100 plate; and driving means connected to the outer end of said through shaft; bolts extending through said frame plate and pump chamber plate, into engagement with said 105 bolt holes in said base flange, arranged to hold said plates in assembled rigid relation with said base; whereby all of the movable portions of said pump may be removed from 110 said base, without disturbing said base or the pipe lines connected therewith.

110 10. In a rotary pump, the combination with a base having a conduit engaging flange and a plane faced flange with an inlet port to said plane face, and an outlet port extending from said plane face, in spaced relation with said inlet port, and a series of bolt holes in said plane faced flange; of means arranged to hold 115 a conduit in communication with said inlet; a pump chamber plate having a series of bolt holes adapted to register with the bolt holes

in said base flange, two ports adapted to register with said inlet and outlet, and a pump chamber between said ports; face plates fitted upon respectively opposite sides of said 5 pump chamber plate, having bolt holes adapted to register with the bolt holes in said base; a frame plate having bolt holes adapted to register with the holes in said chamber plate, face plates and base and having two shaft 10 bearings registering with said chamber; a shaft extending in one of said bearings and exterior to said frame plate; a pump gear connected with said shaft within said chamber; another pump gear in said chamber, in 15 mesh with said first pump gear, and having a shaft rigidly connected therewith, extending in said other shaft bearing in said frame plate; a driving gear fitted to the outer end of said first shaft; bolts extending through 20 said frame plate, face plates and pump chamber plate, into said holes in said base flange, arranged to hold said plates in assembled rigid relation with said base; whereby all of the movable portions of said pump may be removed 25 from said base, without disturbing said base or the pipe lines connected therewith.

10. In a rotary pump, the combination with a base having a conduit engaging flange and a plane faced flange with an inlet port to said plane face, and an outlet port extending from said plane face, in spaced relation with said inlet port, and a series of bolt holes in said plane faced flange; of means arranged to 30 hold a conduit in communication with said inlet; a pump chamber plate having a series of bolt holes adapted to register with the bolt holes in said base flange, two ports adapted to register with said inlet and outlet, and a 35 pump chamber between said ports; a frame plate having bolt holes adapted to register with the holes in said chamber plate, and base and having two shaft bearings registering with said chamber; a shaft extending in 40 one of said bearings and exterior to said frame plate; a pump gear connected with said shaft within said chamber; another pump gear in said chamber, in mesh with said first pump gear, and having a shaft rigidly connected 45 therewith, extending in said other shaft bearing in said frame plate; a driving gear fitted to the outer end of said first shaft; bolts extending through said frame plate and pump chamber plate, into said holes in said base 50 flange, arranged to hold said plates in assembled rigid relation with said base; whereby all of the movable portions of said pump may be removed from said base, without disturbing said base or the pipe lines connected therewith. 55

11. In a rotary pump, the combination with a base having an inlet port and means arranged to connect a liquid supply conduit therewith, and having an outlet port, in 60 spaced relation with said inlet port; of a pair

of intermeshed gears between said inlet and outlet ports, and in communication therewith upon respectively opposite sides of said gears; shafts for said gears; a frame plate having respective journals for said shafts; screw 70 means connecting said frame plate with said base; a driving gear fitted to the outer end of one of said shafts; an intermediate gear, arranged to connect said driving gear with means to operate said pump; an intermediate gear plate fitted to oscillate on said frame plate and having an arcuate slot in concentric relation with said driving gear shaft; and a shaft for said intermediate gear supported 75 by said intermediate gear plate; whereby said intermediate gear may be held in operative position by the screw means connecting said frame plate with said base, and all of the movable parts of said pump may be removed 80 from said base, without disturbing said base 85 or the conduits connected therewith.

12. In a rotary pump, the combination with a base having an inlet port and an outlet port; of a pair of pump gears intermeshed between said ports; shafts for said pump gears; a 90 frame plate having bearings for said shafts; a driving gear, on one of said shafts; an intermediate gear in mesh with said driving gear; and means supporting said intermediate gear, including a plate fitted to oscillate 95 upon said frame plate; and means detachably securing said frame plate to said base plate; whereby all of the movable portions of said pump and its driving gearing may be removed 100 from said base, without disturbing said base 105 or the conduits connected therewith.

13. In a rotary pump; the combination with a base adapted to fit a cylindrical conduit and having an inlet port adapted to register with a port in said conduit; of clamping means arranged to detachably secure said base upon such a conduit; a pump frame plate carrying pumping means independently of said base; means detachably securing said frame plate to said base; a shaft carried by 110 said frame plate and arranged to actuate said pumping means; a driving wheel on said shaft and means arranged to operatively connect and disconnect said driving wheel with respect to a driving mechanism without interruption of the rotation of said driving mechanism; whereby a series of such pumps may be supported by and in communication with a conduit common to all of them and each pump may be independently connected 115 with and disconnected from a driving mechanism common to all of said pumps, without interruption of the operation of said driving mechanism or of the other pumps. 120

14. In a rotary pump, the combination with a base having an inlet port; of clamping means arranged to rigidly connect said base with a supply conduit having a port in registry with the port in said base; of three plane plates, including opposite face plates and an 125

intermediate pump chamber plate, arranged to form a pump chamber; intermeshed gears mounted in said pump chamber; a frame plate carrying means arranged to actuate said gears, independently of said base; and means detachably securing said plates to said base; whereby all of the pump mechanism may be removed from said base without disturbing the connection of the latter with the supply conduit and said face plates may be replaced to compensate for wear without loss of other parts.

15. In a rotary pump, the combination with a pair of symmetrical face plates; of an intermediate pump chamber plate; and means connecting said plates to form a pump chamber housing a pair of intermeshed pump gears; whereby said face plates may be reversed to compensate for wear of said gears upon the inner faces of said face plates.

20. In a rotary pump, the combination with a pair of intermeshed pump gears; of a driving gear operatively connected with one of said pump gears; and means arranged to operatively connect and disconnect said driving gear with a driving train, without interruption of the operation of the latter; including screw means normally maintaining the gears in operative driving relation, arranged

to be axially shifted to permit connection and disconnection of said driving gear train.

25. In a rotary pump, the combination with a pair of intermeshed pump gears; of a driving gear operatively connected with one of said pump gears; and means arranged to operatively connect and disconnect said driving gear with a driving train, without interruption of the operation of the latter; including screw means normally maintaining the parts in operative driving relation; said 30 screw means extending parallel with the axis of said gears and adjustably movable to axially shift said driving gear, to and from its driving position.

35. In a rotary pump, the combination with a pair of face plates; of an intermediate pump chamber plate; means connecting said plates to form a pump chamber; and a pair of intermeshed pump gears in said chamber; whereby said face plates may be changed in 40 position to compensate for wear of said gears upon the inner faces of said face plates.

45. In testimony whereof, I have hereunto signed my name at Philadelphia, Pennsylvania, this twenty-fifth day of February, 50 1926.

ARTHUR E. PAIGE.
